CLAIM

The ornamental design for a baked item, as shown and described.

DESCRIPTION

FIG. 1 is a perspective view of a first embodiment of a baked item showing a new design;
FIG. 2 is a top view thereof;
FIG. 3 is a bottom view thereof;
FIG. 4 is a front view thereof;
FIG. 5 is a rear view thereof;
FIG. 6 is a right side view thereof;
FIG. 7 is a left side view thereof;
FIG. 8 is a perspective view of a second embodiment of a baked item showing my new design;
FIG. 9 is a top view of the baked item of FIG. 8;
FIG. 10 is a bottom view of the baked item of FIG. 8;
FIG. 11 is a front view of the baked item of FIG. 8;
FIG. 12 is a rear view of the baked item of FIG. 8;
FIG. 13 is a right side view of the baked item of FIG. 8;
FIG. 14 is a left side view of the baked item of FIG. 8;
FIG. 15 is a perspective view of a third embodiment of a baked item showing my new design;
FIG. 16 is a top view of the baked item of FIG. 15, which is a mirror image of the bottom view thereof;
FIG. 17 is a front view of the baked item of FIG. 15;
FIG. 18 is a rear view of the baked item of FIG. 15;
FIG. 19 is a right side view of the baked item of FIG. 15; and,
FIG. 20 is a left side view of the baked item of FIG. 15.
